UNITED STATES PATENT OFFICE

100,881

DESIGN FOR AN ORNAMENT FOR A SHOE
OR OTHER ARTICLE OF WEARING AP-
PAREL

Theodore R. Samuels, St. Louis, Mo.

Application June 10, 1936, Serial No. 63,217

Term of patent 3½ years

To all whom it may concern:

Be it known that I, Theodore R. Samuels, a citizen of the United States residing at 5565 Lindell Boulevard, St. Louis, in the State of Missouri, have invented a new, original and ornamental Design for an Ornament for a Shoe or Other Article of Wearing Apparel, of which the following is a specification, reference being had to the accompanying drawing, forming a part thereof.

In the accompanying drawing Figure 1 is a view in plan of an ornament showing my new design; and Fig. 2 is a view in front elevation.

I claim:

The ornamental design for an ornament for a shoe or other article of wearing apparel, substantially as shown.

THEODORE R. SAMUELS.
